UNITED STATES PATENT OFFICE

2,534,417

MUSICAL INSTRUMENT

Christopher C. Dargis, Ridley Park, Pa.

Application December 9, 1947, Serial No. 790,520

4 Claims. (Cl. 84—404)

1

My invention relates to new and useful musical instruments and more particularly to a small sized apparatus including a combination of various instrumentalities that will produce sweet, soft, delicate and agreeable musical sounds which are enchanting to listeners.

An object of my invention is to provide a musical instrument of light weight that can be partly folded to occupy a small space and capable of being readily transported by hand for employment with a small band, orchestra or other group of musicians which may have an engagement at a place where no similar instrument is otherwise available.

Another object of the invention is to so construct the case and mechanism that the hammers are held in locked position when the lid is closed and released when said lid is raised.

Another object of this invention is to provide a resonator box within the case and associated with the sound producing means, said resonator box having transverse partitions to divide the box into several chambers.

Another object of the present invention is to use glass bars, either solid or tubular, as some or all of the sound producing means.

Another object of this invention is to provide unique means for suspending the glass bars.

With the above and other objects in view this invention consists of the details of construction and combination of elements hereinafter set forth and then designated by the claims.

In order that those skilled in the art to which this invention appertains may understand how to make and use the same I will describe its construction in detail referring by numerals to the accompanying drawings, forming a part hereof, in which:

Fig. 1 is a front view of the instrument with the lid partly elevated and portions of the legs broken away.

Fig. 2 is an end of the instrument set up and the lid closed.

Fig. 3 is a similar view with the legs folded and a handle extended so the instrument may be carried by hand for transportation purposes.

Fig. 4 is an enlarged top plan view of the instrument with the lid open thereby releasing some of the parts to permit playing thereof.

Fig. 5 is a section on the line 5—5 of Fig. 4, with the lid closed.

Fig. 6 is an enlarged cross sectional view of a number of the sound producing means in the form of tubular glass bars and the suspending means.

2

Fig. 6a is a view, partly in section and partly diagrammatic, illustrating the arrangement of the hangers.

Fig. 7 is a sectional view of Fig. 6 at right angles thereto.

Fig. 8 is a section on the line 8—8 of Fig. 4, with the lid closed.

Fig. 9 is an enlarged fragmentary sectional view similar to Fig. 5 with an action unit in operative position.

Fig. 10 is an enlarged plan view of the resonator box removed from the instrument case.

Fig. 11 is a section on the line 11—11 of Fig. 10.

Fig. 12 is a section on the line 12—12 of Fig. 10.

In carrying out my invention as herein embodied 20 represents the case having a key-board extension 21 along the front. This case is shaped like a truncated trapezium, that is, it is oblong with a portion of the rear formed at an angle to the front so that the space between the front and rear gradually decreases in width from a location spaced from the left hand end or side to the opposite or right end or side.

The lid 22 is of the same outline and is hinged at 23, Fig. 4, at the upper edge of the rear or truncated portion of the case. Said lid may be supported in an elevated position by a prop 24 swingingly connected at 25 to the inside of the forward ledge of the lid and adapted to rest on the upper edge of the front wall of the case between hammer brackets or clips to be later described.

The case 20 and component parts are supported on legs 25 which are foldable or removable when the device is being transported and, for purposes of illustration only, said legs are shown pivoted at 26 and braced laterally by cross pieces 27 and further supported by struts 28 swingingly attached to the case and detachably connected with the front legs.

In order to easily transport the instrument, a carrying handle 29 is pivoted at 30 to the underneath edge of the case 20 so as to be swung out of the way, as in Fig. 2, or projected forwardly, as in Fig. 3.

Within the case 20 is mounted the resonator box 31 which is in the general shape of a trapezium so as to follow the approximate outline of the case with the smaller end positioned towards the treble end of the instrument. The ends of said resonator box are attached to the ends of the case in any suitable manner and may be further supported by one or more braces 32, Fig. 5, secured to a wall of said case and to said resonator box.

The resonator box includes an imperforated

bottom 33, a front wall 34, and walls 35 and a top wall 36, the latter having a row of holes 37 located approximately midway between the front and back edges and decreasing in size or diameter from the wider towards the narrower end. The rear of the resonator box is normally open. Within the resonator box are a number of partitions 38, Figs. 10 and 11, which run transversely or from front to back and these are spaced longitudinally of the resonator box, the distance between them decreasing from the larger end of said resonator box towards the smaller or treble end thereof. The resonator box is tuned to the sound producing bars, to be presently described, by mounting adjustable stoppers 31a in the compartments formed by the partitions. These stoppers make the compartments in harmony with the sound producing bars.

Over the narrower portion of the resonator box 31 and spaced above the same is a generally triangular shaped or trapezoid frame 39 including front and back or side rods 40 and end rods 41, Figs. 4, 5, 6, 7 and 9, supported in any suitable manner. The side rods 40 on said frame 39 each have a longitudinal groove 42 with which communicate a series of equally spaced vertical holes 43, Fig. 6, spaced according to the spacing of the sound producing bars 44, which in this instance, are shown as round and tubular in form, and which may vary in diameter, thickness and length.

Flexible hanging means 45 and 45a, such as strings, is threaded back and forth through the series of holes 43, in alternating relation, in each side rod 40 and looped around the respective sound producing bars, Fig. 6a, to support the latter at or adjacent both ends thereof so that they are hangingly suspended directly above the resonator box. Said flexible hanging means between holes 43 lies in the groove 42, at least a short distance below the top surface of the side rods 40.

Because the sound producing bars 41 are suspended in stirrup-like hanging means said sound producing bars can slide or move longitudinally and to prevent undue shifting a stationary stop 46 is mounted on the forward portion of the resonator box 31. The face of the stop opposing the sound producing bars is covered with suitable compressible or cushioning material 47, such as felt. At the rear of the sound producing bars 41 is a movable stop 48, Fig. 5, pivoted at 49 and normally urged into a retracted position, away from the rear ends of said sound producing bars 41, by one or more springs 50, Figs. 4 and 5. This movable stop has suitable compressible or cushioning material 51 on the face opposing the sound producing bars and may be manually moved towards and into contact with the rear ends of said sound producing bars for moving the latter towards the stationary stop for the purpose of aligning all of said sound producing bars. For conveniently operating the movable stop against the action of the resilient means 50, a handle or knob 52 is mounted on said movable stop 48. Other equivalent means can be substituted for the handle or knob, such as a treadle mechanism, and said movable stop can then be conveniently used as a damper.

The sound producing bars 53 at the bass end of the instrument are flat members of glass or other suitable material and vary in length, in particular, and sometimes in width and thickness to produce the proper sounds or tones. The forward ends of the sound producing bars 53 are

15 suspended similar to the bars 44 and for this purpose a rod 54, Figs. 4 and 8, is mounted a suitable distance above the resonator box in an oblique position relative to the front wall of the case and one end is secured to an end rod 41 of the frame 39 and the other end is attached to an end wall of the case. This rod 54 is constructed similar to the rods 40 of the frame 39 in that it has a longitudinal groove 55 and vertical holes 56, Fig. 8, so that flexible hanging means 57, such as string, can be threaded through the holes and passed under the forward ends of the sound producing bars 53 to suspend said forward ends, and the upper portions of the hanging means will lie 15 in the groove.

The rear ends of the sound producing bars 53 rest on a strip of felt 58, or equivalent material, mounted on top of the resonator box 31 and the rear ends of said sound producing bars 53 are 20 loosely held in place by pins 59 passing through holes larger than pins in said sound producing bars 53. Felt or soft leather washers 60 are mounted on the pins between their heads and the sound producing bars 53.

25 The playing action includes the white and black keys 61 and 62 respectively, and all of them have their ends mounted on a rocker bar 63 and held against accidental displacement by pins 64 fixed in the rocker bar and loosely fitting in holes in 30 the keys, which holes are larger than the pins.

A prolong or connecting rod 65 of wire is slidably connected to each key by passing the same through the key and providing a head 66 on the lower protruding end thereof. The upper end 35 of the prolong or connecting rod 65 is attached to the enlarged portion or foot 67 of the hammer shank 68 carrying the hammer 69. The foot 67 of each hammer is positioned in a notch in a mounting clip 70 secured to the front wall of the case. Said foot 67 is connected to the mounting clip by a pivot 71 and has a shoulder 72 coacting with the clip to limit the upward movement of the hammer. If advisable or desirable each prolong or connecting rod 65 may slidably operate 40 through a guide 73 projecting from the front wall of the case.

A tiltable frame 74, Figs. 4, 5, 8 and 9, including side arms 75 and cross rods 76 and 77, is hingedly or swingingly mounted at the outer ends of said arms to a suitable portion of the front of the instrument case, as the front wall thereof, and the cross rods overlie the shanks 68 of all of the hammers at spaced locations. The cross rod 77 has its under face covered with 50 a strip of felt 78 or other suitable cushioning material against which the shanks of the hammers strike as they are drawn upward by the springs 79 each of which has an end attached to a separate hammer, particularly the foot 67 thereof, and the other end to the cross rod 76 of the tiltable frame 74.

When the frame 74 is depressed, as shown in Figs. 5 and 8, the hammers will likewise be depressed and the lid can be closed. Upon depression of the frame 74 and the hammers, the prolong or connecting rods 65 will slide a short distance through their respective keys. When 65 said tiltable frame 74 is elevated, after the lid has been opened, the springs 79 will cause the hammers to follow said tiltable frame and also be elevated. This will move the prolong or connecting rods 65 into operative position with relation to the keys and the tiltable frame 74 is temporarily retained in its elevated position by a prop 80 loosely connected at one end to said

tiltable frame, and especially the cross rod 16 thereof, while the other or free end of said prop 80 is adapted to rest on some stationary element, such as the resonator box 31. When the tiltable frame is depressed, the weight of the parts will cause it to remain so and the prop 80 will hang free.

With the tiltable frame elevated the playing action is in position for use and when a key is actuated its associated hammer will be operated through the respective prolong or connecting rod and then returned by its respective spring 79.

From the foregoing it will be apparent that I have provided a musical instrument that is compact, light in weight, although strong and durable, and one which may be partially collapsed and readily transported by hand from one locality to another. Particular attention is called to the retractable action which permits the mechanism to be housed in a case of small dimensions, and the resonator box which will reenforce the sound tones considerably although relatively small in size and of light weight.

Of course I do not wish to be limited to the exact details of construction herein shown and described as these may be varied within the scope of the appended claims without departing from the spirit of my invention.

Having described my invention what I claim as new and useful is:

1. A musical instrument comprising a case, a resonator box decreasing in width from the bass end to the treble end and open at the back, the top wall of said box having holes in the longitudinal axial center and decreasing in size from the bass towards the treble end and the interior divided into transverse compartments decreasing in width longitudinally of said box from the bass to the treble end thereof, a frame mounted in the case above the resonator box, said frame including front, back and end rods, said front and back rods extending over slightly more than one-half of the resonator box from the end thereof and having vertical holes therethrough, flexible hanger means threaded back and forth through the holes in said rods to provide depending loops, tubular glass sound producing bars of different lengths suspended in the loop portions of said flexible hanger means, an individual rod mounted in the case above the bass or wider portion of the resonator box adjacent the forward edge thereof and having vertical holes therethrough, other flexible hanger means threaded through said last named holes to provide loops, flat glass sound producing bars of different lengths having one end of each suspended in the respective last mentioned loops, means passing through the rear ends of the flat sound producing bars and fixed in the resonator box to hold said flat bars in place, a strip of cushioning material between the resonator box and the rear ends of

5 said flat bars, a tiltable frame hingedly connected to the front of the case above the sound producing bars and including a pair of spaced longitudinal cross rods, cushioning material on the underneath face of the outer cross rod of said tiltable frame, a playing action including hammers and their shanks pivoted to the forward portion of the case and located between the cross rods of the tiltable frame and the sound producing bars, springs connecting the individual hammer elements with the inner cross rod of said tiltable frame whereby said hammer elements may be caused to follow the movements of said tiltable frame for retracting and extending the hammer elements, and means for holding the tiltable frame in an extended position.

2. The musical instrument of claim 1, in combination with a stationary stop on the resonator box in opposition to the forward ends of the tubular sound producing bars, a movable stop beyond the rear ends of said tubular sound producing bars to be moved into contact with the rear ends of said tubular sound producing bars, and means to urge said movable stop away from said sound producing bars.

3. A musical instrument according to claim 1, in combination with stoppers adjustably mounted in the resonator box compartments for harmonizing different areas of said resonator box with the adjacent sound producing bars.

4. A musical instrument comprising a case including a hinged lid, sound producing bars positioned in definite locations within the case, a tiltable frame hingedly connected inside of said case to a wall thereof and above the sound producing bars and swingable towards and away from the latter, a playing action including hammers and their shanks pivoted to the same wall of the case on which the tiltable frame is hinged and underlying said frame, and means to urge said hammers towards said frame whereby said hammers will follow the movements of said frame.

CHRISTOPHER C. DARGIS.
